UNITED STATES PATENT OFFICE

2,550,457

MULTICYLINDER REFRIGERANT
COMPRESSING APPARATUSWayne E. Dodson, Caldwell, N. J., assignor to
General Electric Company, a corporation of
New York

Application December 21, 1949, Serial No. 134,249

2 Claims. (Cl. 230—2)

1

My invention relates to refrigerant compressing apparatus having two or more compression cylinders and particularly to such apparatus wherein the capacity may be varied by by-passing one or more of the cylinders.

In refrigerating apparatus it is frequently desirable to provide some arrangement for changing the effective capacity of the compressor. In some installations it is desirable that changes in capacity may be effected without changing substantially the average speed of the compressor, and one method for accomplishing this purpose is to return to the suction line the refrigerant gas compressed in one or more of the cylinders. Accordingly it is an object of my invention to provide a multicylinder compressing apparatus having provision for by-passing one or more of the cylinders and including an improved arrangement for minimizing the heating of the by-passed cylinders by recirculation of compressed refrigerant.

Further objects and advantages of my invention will become apparent as the following description proceeds, and the features of novelty which characterize my invention will be pointed out with particularity in the claims annexed to and forming a part of this specification.

In carrying out the objects of my invention, I provide a compressing apparatus in which one or more of the cylinders is arranged to be bypassed so that the refrigerant pumped therein is returned to the suction line. The discharge connection from the by-passed cylinder is arranged to convey the pumped refrigerant directly to the intake of an active cylinder so that the gas discharged from the by-passed cylinder enters the active cylinder rather than being recirculated through the by-passed cylinder, which would thereby be subject to excessive heating.

For a better understanding of my invention, reference may be had to the accompanying drawing, the single figure of which represents diagrammatically an air cooling system provided with a refrigerating machine embodying my invention.

Referring now to the drawing, air circulated by a suitable blower (not shown) passes through a duct 10 over the coils of an evaporator 11. The evaporator is supplied with liquid refrigerant from a liquid receiver 12 through a liquid line 13 under control of a suitable refrigerant flow-control device, such as a thermostatic expansion valve 14, this valve having a temperature responsive element 15 secured in heat exchange with the outlet of the evaporator 11. Refrigerant vaporized in the evaporator by absorption of heat from

2

the air flowing through the duct 10 is removed through a suction line 16 by operation of a compressing apparatus 17. The apparatus 17 comprises two cylinders 18 and 19 which are driven by the same motor (not shown) and comprise a multicylinder compressor. Suction line 16 is connected to the intakes of the cylinders 18 and 19 by conduits 20 and 21 respectively, and the refrigerant compressed in the cylinders 18 and 19 is delivered through discharge conduits 22 and 23 respectively to a condenser 24. The hot compressed refrigerant in the condenser 24 is cooled by heat exchange with air, water or other suitable cooling fluid circulated over the surface of the condenser by suitable pumps or blowers (not shown), and the refrigerant liquefied in the condenser then flows by gravity to the liquid receiver 12.

When the load demand on the compressor 17 has been reduced during the cooling operation, it may be desirable to continue the operation of the compressor at reduced capacity, and in order to effect a reduction in capacity the discharge conduit 23 of the cylinder 19 is arranged to be connected to the suction line through a conduit 25 having a normally closed solenoid valve 26 therein. The demand for reduced loading may be determined, for example, by reduction in the suction pressure below a predetermined value, and a bellows 27 is connected through a duct 28 to the suction line for this purpose. When the suction pressure falls to a predetermined value, the bellows 27 contracts sufficiently to move a link 29 on a switch mechanism 30 over the center line of a spring 31 so that the spring moves a switch arm 32 into engagement with a contact 33. This connects a solenoid 34 of the valve 26 to electric power lines 35, the solenoid being connected to one side of the lines 35 and the switch arm 32 being connected to the other side through a line 36. When the solenoid 26 is opened, refrigerant compressed in the cylinder 19 is discharged directly through the conduit 25 to a suction connection 37 of the cylinder 18, this being the connection to which the suction conduit 20 is also connected. Return of compressed refrigerant to the cylinder 19 through the conduit 23 is prevented by a check valve 38. Thus when the valve 26 is opened, refrigerant pumped by the cylinder 19 is returned directly to the suction or low pressure side of the system and the cylinder is thus unloaded.

Refrigerant vaporized in the evaporator 11 flows to both cylinders 18 and 19 from the suction line 16; however, because the discharge or by-

pass conduit 25 conducts refrigerant from the cylinder 19 directly to the intake connection 31 of the cylinder 18, the cylinder 18 receives the heated refrigerant from the cylinder 19 while the cylinder 19 receives substantially only the cool refrigerant from the suction line 16. In order to make sure that substantially all the gas discharged from the by-passed cylinder 19 enters the cylinder 18, the pistons of the two cylinders, as indicated by dotted lines on the drawing at 39 and 40 respectively, are arranged to be driven so that the intake portion of the cycle of the cylinder 18 occurs during the discharge portion of the cycle of the cylinder 19. The cylinders 18 and 19 may, for example, be only two cylinders of a compressor having four or more cylinders, and obviously the by-passed cylinders may each be arranged to discharge by-passed refrigerant to a working cylinder having its intake stroke occurring during the discharge stroke of the respective by-passed cylinder. Thus the by-passed refrigerant is not returned to the common suction line but passes directly to the intake of a working cylinder. With this arrangement, recirculation of refrigerant heated in the unloaded cylinder 19 is minimized and continued increase in the temperature of the cylinder 19 due to such recirculation is prevented.

It will be obvious that any suitable control may be provided for opening and closing the valve 26 when by-passing of the cylinder 19 is desired and that the operation of the valve 26 in response to suction line pressure has been illustrated and described merely by way of example.

The refrigerant circuit described above effectively avoids the excessive heating which may occur in conventional practice wherein refrigerant from by-passed cylinders is returned to the common suction line so that a substantial portion thereof is returned to the by-passed cylinders and thereby effects an undesirable increase in the temperature of these cylinders.

What I claim as new and desire to secure by Letters Patent of the United States is:

1. A refrigerant compressing apparatus adapted to be connected in a closed refrigerant circuit and comprising a plurality of compressor cylinders each having an inlet and an outlet, an intake connection for said apparatus, a discharge connection for said apparatus, separate conduit means for connecting said intake connection respectively to each of said inlets, means for connecting said outlets of said cylinders to said discharge connection and for preventing reverse flow of refrigerant therefrom to the outlet of one of said cylinders, conduit means connecting

the outlet of said one of said cylinders to the inlet of another of said cylinders at said other cylinder and remote from said intake connection, and means dependent upon a condition of operation of said apparatus for controlling said last-mentioned conduit means to effect unloading of said one cylinder and the discharge of refrigerant therefrom directly to the intake of said other cylinder, said apparatus including means for controlling the cycle of said one cylinder to effect discharge of refrigerant therefrom during the intake portion of the cycle of said other cylinder, whereby the hot compressed refrigerant is directed preferentially to said other cylinder and the recirculation of refrigerant discharged from said one cylinder is minimized.

2. A refrigerant compressing apparatus adapted to be connected in a closed refrigerant circuit and comprising a plurality of compressor cylinders each having an inlet and an outlet, an intake connection for said apparatus, a discharge connection for said apparatus, a common intake conduit communicating at its ends with said inlets for said cylinders, means providing communication between said intake connection and said intake conduit intermediate the ends of said conduit, discharge conduits connecting the outlets of said cylinders and said discharge connection, conduit means including a normally closed valve and connecting the outlet of one of said cylinders with the inlet of another of said cylinders adjacent the corresponding end of said common conduit and remote from said intake connection, and means for opening said valve to effect unloading of said one cylinder and the discharge of refrigerant therefrom directly to the intake of said other cylinder, said apparatus including means for controlling the cycle of said one cylinder to effect discharge of refrigerant therefrom during the intake portion of the cycle of said other cylinder, whereby recirculation of refrigerant discharged from said one cylinder is minimized.
